COMBINATION VACUUM CHAMBER AND HIGH VOLTAGE TERMINAL

David A. Swick, R.R. 1, Box 580, Accokeek, Md.
Continuation of application Ser. No. 98,989, Mar. 28,
1961. This application June 12, 1963, Ser. No. 288,587

5 2 Claims. (Cl. 174—18)

(Granted under Title 35, U.S. Code (1952), sec. 266)

The invention described herein may be manufactured 10 and used by or for the Government of the United States of America for governmental purposes without the payment of any royalties thereon or therefor.

The present invention is a continuation of application Serial No. 98,989, filed March 28, 1961, now abandoned, and relates to means for conducting electrical voltages into a chamber and more particularly to an electrical terminal adapted to conduct high voltages into a vacuum chamber.

Heretofore terminals have been constructed which consist of glass-to-metal seals through which a conductor is passed to conduct an electrical voltage through the walls of a chamber. Such terminals have their drawbacks wherein the glass-to-metal seals break easily, and for use with a vacuum system, the glass-to-metal seals leak or outgas such that a vacuum cannot be efficiently maintained in a chamber into which the electrical voltage is directed. In order to prevent a high voltage breakdown and in order to protect personnel from contact with high voltage in systems wherein a high voltage is directed into a chamber in which the walls are grounded, it is required that a seal be maintained between the conductor at high voltage and the grounded wall.

It is therefore an object of the present invention to provide an electrical terminal suitable for conducting high voltages into a vacuum system in which the walls of the vacuum system are grounded.

Another object is to provide an electrical terminal which is nonbreakable and will maintain a good vacuum seal.

Another object is to provide an electrical terminal which will assure adequate pressure in the vacuum system into which an electrical voltage is conducted.

Yet another object is to provide an electrical terminal which is simple in structure, relatively small in size, relatively inexpensive, easy to assemble, and yet is sufficiently rugged to withstand high voltages.

Other and more specific objects of this invention will become apparent upon a more careful consideration of the following detailed description when taken together with the accompanying drawing in which the drawing is a cross section of the device which illustrates the features of the invention.

The electrical terminal comprises a polytetrafluoroethylene insulator (which is known and sold by its trademark term, Teflon) which fits within a brass or other metallic conductor in which the brass conductor is secured to the wall of a vacuum chamber. The Teflon insulator is made such that an electrical terminal is secured within it. An electrical conductor is passed through the Teflon insulator into a vacuum chamber through the walls thereof. A vacuum is maintained in the vacuum chamber through use of gaskets wherein the gaskets have a minimum exposure to any through cracks or openings into the vacuum system. Electrical contact is made with the terminal through a brass or other metallic plate held in place by a compression spring which is connected through a fuse wire and a surge resistor to an electrical conductor cable which is shielded about the outside. The shield about the outside of the cable is connected to the brass conductor to complete the circuit with the grounded wall of the vacuum chamber.

Now referring to the drawing, there is shown a cross sectional view of a device which comprises an elongated metal tubular cylinder 11 which may be made of brass or any other suitable conductor which has a radially extending flange 12 at one end and a flange 13 at the opposite end. Flange 12 is provided with suitable holes or passages 14 therein through which bolts 15 may be passed to secure the cylindrical member to the wall 16 of a vacuum chamber or system through which an electrical high voltage is to be passed. Flange 13 is provided with screw threaded holes 17 therein which receive suitable screw threaded screws such as 18. The tubular member 11 provides a conductive sleeve which receives a tubular Teflon insulator 21 or an insulator made of a similar material which has an elongated end 22 of the same length as the sleeve and fits therein with a snug fit. The insulator is provided with a radial flange 23 which extends along the flange 12 of the sleeve a distance slightly less than the distance to the holes 14 which pass through the flange 12 and has an end 24 which extends from the flange into the vacuum chamber through an aperture in the chamber wall 16. The outside diameter of the insulator is equal to the inner diameter of the Teflon sleeve and the inner diameter of the insulator is slightly greater than the supply cable used. The inner surface of the insulator 25 opposite to the flange 12 is provided with a ridge or a radial inwardly extending flange 25 which extends inwardly from the wall surface in a plane with flange 23 and includes a passage 26 from the end 22 to the end 24. The ridge 25 is provided with holes 27 passing therethrough, the purpose of which will be explained later. A brass or any other suitable metallic conductor 30 having linear portions of different radii is inserted through the end 24 of the insulator with the central portion 31 fitting snugly into passage 26 with an end 32 of smaller diameter that extends into the area bounded by the end portion 22 of the insulator. The conductor is also provided with an enlarged portion 33 which extends along the vacuum side of the ridge 25 and has a diameter 40 slightly less than the inner diameter of the insulator end 24. The end 33 of the conductor has blind threaded holes 34 therein which receive the end of bolts 35 which pass through the holes 27 in the ridge 25. The bolts 35 pass through a pressure ring 36 on the air side of the ridge 25 and a gasket 37 is secured between the pressure ring 36 and the ridge 25 which closes the air space between the central portion 31 of the conductor 30 and the passage 26 between the end sections 24 and 22 of the insulator. The screws 35 pass through the pressure ring 36 and the gasket 37 and the ridge 25 and screw into the threaded holes 34 of end 33 of the conductor 30 whereby the screws are tightened against the gasket to seal the space between ridge 25 and the section 31 of the conductor 30. Such an assembly provides a vacuum seal between the ridge 25 and the largest portion 33 of the conductor 30 and also between the ridge 25 and the gasket 37. Furthermore, there is no straight through crack which would permit a leak. The portion 33 of the conductor 30 has a blind hole therein within which a wire connector 38 can be secured to electrically connect a conductor 39 thereto. The electrical conductor then connects at the other end to the element to which the high voltage is to be supplied. The connector 38 has channels in it to permit rapid vacuum pumping of any gas trapped between it and conductor 30.

65 The opening in the vacuum wall to which the vacuum seal terminal is connected is made in a step configuration to receive the insulator from the air side of the vacuum wall. The opening on the vacuum side is of a diameter only large enough to receive the end 24 of the insulator. The portion of the opening in the vacuum wall that is 70 toward the air side is of a diameter larger than that por-

tion toward the vacuum side and is sufficiently large to receive the flange 23 of the insulator. A gasket 41 is placed between the flange 12 of the sleeve 11 and the wall surface 16 of the vacuum chamber such that the gasket covers a portion of the surface of flange 23 and the wall surface of the vacuum chamber 16 to cover the crack joint between the two members 16 and 25. Bolts 15 are passed through the flange 12 and screwed into the vacuum wall surface 16 and tightened such that the gasket 41 will compress and insure a vacuum seal between the insulating member 21 and the vacuum wall 16.

The cylindrical outer conductive sleeve 11 is provided with a plate 42 at the outer end which is secured thereto by screws 18 which screw into the flange 13 of the cylindrical sleeve 11. The plate 42 is provided with an axially extending opening therein with a wall surface perpendicular to the plate surface. The wall surface 43 is provided with screw thread openings which receive screws 44, the purpose of which will be explained later.

A high voltage is transmitted from a voltage source 40 to the vacuum seal conductor by a cable which includes a grounded shield 45, and a center wire 46 which are separated by an insulation material 47. The grounded shield 45 is stripped back a short distance from the end of the cable and the stripped end of the cable including the insulation and the wire is inserted into the end 22 of the insulator 21 through the axial opening of the plate 42. The grounded shield is connected to the wall 43 of the plate 42 by screws 44, this connection provides a ground contact with the vacuum wall 16 through the metal cylindrical sleeve 11 which is connected to the wall surface by screws 15. The high voltage is transmitted from the wire through a surge resistor 48 which is connected to a fuse wire 51. The fuse 51 is connected to a brass plate 52 which is held in position by a Teflon holder 53. A spring 54 is soldered to the plate 52 and to another plate 55 which is forced against the end 32 of the brass conductor 30. Therefore, electrical voltage passes from the wire 46 to the conductor 30 through the surge resistor 48, the fuse 51 and the spring brass plate arrangement 52, 54 and 55. The Teflon holder 53 is made in two pieces 57 and 58. The piece 57 has an outside diameter equal to the diameter of the end of the cable which is inserted into the end 22 of the Teflon insulator 21. The portion 57 has a partition therein which acts as a means for holding one end of the resistor 48. The end furthest removed from the cable has a portion 61 which has an inner diameter greater than the inner diameter of the other portion. Such an arrangement affords a seat for the brass plate 52 which is held in place by the upper portion 58 of the Teflon holder. The upper portion has an outer diameter which is equal to the inner diameter of the insulator 21 and has a portion 62 connected therewith which is inserted into the end portion 61 of the piece 57 of the insulator holder. The brass plate 55 is made of such a diameter that it will slide within the inner diameter of the part 58 of the holder 53. The spring 54 forcing against the secured plate 52 and the movable plate 55 insures a good electrical contact with the end 32 of the conductor 30.

In carrying out the assembly of the device the vacuum sealed conductor 30 is secured in place by screws 35. Insulator 21 is fitted with the end 22 into the sleeve 11 and secured to the vacuum wall 16 by screws 15 with suitable gaskets between the surfaces. The grounded shield of the cable is removed for a short distance along the end of the wire and the cap 42 is slipped over the cable and secured thereto with the screws 44. The resistor, fuse, brass plates and spring arrangement is fitted into the Teflon holder 53 and the outer end of the resistor 70 is connected to the wire 46 of the cable. The Teflon holder arrangement is passed into the end 22 of the insulator along with the stripped end of the cable and then the cap 42 is secured to the sleeve 11 by bolts 18. Since the cable is held in place in the cap 42 by bolts 44, 75

the spring 54 will hold the brass plate 55 in contact with the end 32 of the vacuum sealed conductor 30.

Such an arrangement affords a vacuum tight electrical terminal suitable for conducting high voltages into a vacuum system through the grounded walls of the vacuum system. Such an arrangement provides a minimum surface subject to outgassing and is made of a material which is not subject to breakage or electrical breakdown.

The high voltage terminal has been described as useful for a grounded vacuum chamber wall wherein the sleeve about the insulator completes a circuit to ground. Such a high voltage terminal can be used in a vacuum tube or any other structure wherein oppositely disposed terminals can be secured in an insulator and a filament or conductor connected between the two terminals without a ground connection to the wall of the tube. In such an arrangement the insulator could be connected to the tube structure by a flange which has a shoulder that extends over the flange of the insulator. Thus the insulator would be secured in position by pressure applied to the insulator flange by the shoulder on the securing flange. In this manner the terminal would be insulated from the tube wall and the circuit could be completed by a connection with each terminal.

Obviously many modifications and variations of the present invention are possible in the light of the above teachings. It is therefore to be understood that within the scope of the appended claims the invention may be practiced otherwise than as specifically described.

30 What is claimed is:

1. In combination, a vacuum chamber and a high voltage electrical terminal that makes an electrical connection between the vacuum side and the non-evacuated side of said vacuum chamber to transmit a high voltage from a power source into said vacuum chamber whose walls are at ground potential which comprises:
an aperture in one wall of said vacuum chamber,
(a) an elongated tubular insulator secured in said aperture in said wall of said vacuum chamber,
(b) said tubular insulator including one end that extends beyond said wall into said vacuum chamber and an end which extends outwardly from said non-evacuated side of said chamber,
(c) an integral flange on the outer perimeter of said tubular insulator that extends radially along the wall of said vacuum chamber a short distance surrounding said aperture therein,
(d) an integral flange on the inner periphery of said insulator,
(e) an aperture in said inner flange forming an opening between the ends of said insulator,
(f) an electrical conductive sleeve,
(g) said electrically conductive sleeve surrounding said tubular insulator portion that extends outwardly from said chamber,
(h) a radially extending flange on the periphery of said conductive sleeve at the end thereof toward said vacuum chamber extending along said integral flange on the perimeter of said tubular insulator,
(i) said flange on said sleeve extending along said integral flange on the outer perimeter of said insulator and said vacuum chamber wall a greater distance than said flange on the outer periphery of said tubular insulator,
(j) means securing said conductive sleeve flange to said chamber wall thereby forcing said conductive sleeve flange against said integral flange on the outer perimeter of said tubular insulator to secure said insulator flange against the wall of said vacuum chamber,
(k) said conductive sleeve forming a ground conductor as well as providing protection for said insulator sleeve,
(l) an electrical terminal conductor,

- (m) said electrical terminal conductor having a portion thereof extending along the vacuum side surface of said inner flange on the insulator and a portion extending through said aperture and into the area confined by said insulator on the non-evacuated side of said chamber, and
- (n) means for securing said electrical terminal conductor in a vacuum tight seal to said inner flange on said insulator element.
2. In combination, a vacuum chamber and a high voltage electrical terminal that makes an electrical connection between the vacuum side and the non-evacuated side of said vacuum chamber to transmit a high voltage from a power source into said vacuum chamber whose walls are at ground potential, which comprises:
- an aperture in one wall of said vacuum chamber,
- (a) an elongated tubular insulator secured in said aperture in said wall of said vacuum chamber,
- (b) said tubular insulator including one end that extends through said aperture in said vacuum chamber beyond said wall into said vacuum chamber and an end which extends outwardly from said non-evacuated side of said chamber,
- (c) an integral flange on the outer perimeter of said tubular insulator extending radially along said wall surface for a short distance surrounding said aperture therein,
- (d) an integral flange on the inner periphery of said insulator in a plane with said integral flange on the outer perimeter of said insulator,
- (e) an axial aperture within said integral flange on the inner periphery of said insulator,
- (f) an electrical conductive sleeve,
- (g) said electrical conductive sleeve surrounding said tubular insulator portion extending outwardly from said chamber,
- (h) a radially extending flange on the periphery of said conductive sleeve at the end thereof ad-

10

- jacent said vacuum chamber extending along said integral flange on the perimeter of said tubular insulator,
- (i) said flange on said sleeve extending along said integral flange on the outer perimeter of said insulator and the wall of said vacuum chamber a greater distance than said flange on the outer periphery of said tubular insulator,
- (j) means securing said conductive sleeve flange to said chamber wall thereby forcing said conductive sleeve flange against said integral flange on the outer perimeter of said insulator to secure said insulator flange against the wall of said vacuum chamber,
- (k) said conductive sleeve forming a ground conductor as well as providing protection for the insulator sleeve,
- (l) an electrical terminal conductor,
- (m) said electrical terminal conductor having a portion thereof extending along the vacuum side surface of said inner flange on the insulator and a portion extending through said aperture and into the area confined by said insulator on the non-evacuated side of said chamber, and
- (n) means for securing said electrical terminal conductor in a vacuum tight seal to said inner flange on said insulator element.
